(57) **CLAIM**

The ornamental design for an electric fan as shown and described.

DESCRIPTION

FIG. 1 is a perspective view of an electric fan showing this design;

FIG. 2 is another perspective view of an electric fan showing this design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a detail view of the portion within the box of FIG. 1.

The even broken lines depict portions of the electric fan and the uneven broken lines depict boundaries of the detailed view. Both broken lines form no part of the claimed design.
